UNITED STATES PATENT OFFICE.

FREDERIC W. BUTT, OF BROOKLYN, NEW YORK, ASSIGNOR OF TWO-THIRDS TO
CORNELL S. HAWLEY, OF ALBANY, NEW YORK.

DEFLECTOR FOR HEAT-RADIATORS.

1,098,224.

Specification of Letters Patent.

Patented May 26, 1914.

Application filed November 24, 1911. Serial No. 662,164.

To all whom it may concern:

Be it known that I, FREDERIC W. BUTT, a citizen of the United States, residing at Brooklyn, in the county of Kings and State 5 of New York, have invented new and useful Improvements in Deflectors for Heat-Radiators, of which the following is a specification.

This invention relates to deflectors for 10 heat radiators which are placed beneath seats, and it is particularly applicable to the stationary, cross or longitudinal car-seats of passenger cars.

One of the objects of the invention is to 15 provide a simple and inexpensive device for attachment to the radiator, which will deflect the heat from underneath the seat cushion and away from same and prevent the body of the seat as well as its sides from 20 becoming unduly heated, thereby obviating one of the discomforts of traveling. By this invention the heated air is kept constantly in motion and directed to the rear of the seat or to one or both of its ends, thus 25 preventing the currents from becoming pocketed beneath the seat cushion.

Another object of the invention is to provide a heat deflector which is easily attached to the radiator and with it to the 30 frame of the car seat and which is also detachable from both the radiator and the car seat-frame.

Referring to the drawings, Figure 1 is 35 a rear elevation of a typical car-seat to which the invention is applied. Fig. 2 is an end-elevation with the seat-frame in section. Fig. 3, is a rear elevation, with parts broken away, showing a modified form of deflector; and Fig. 4, is a sectional view on 40 the line X—X of Fig. 3.

The car-seat comprises cushion 1 and back 2 supported by seat-frame 3 which is mounted at one end on a pedestal 4 and suitably attached at the other end to car- 45 side 5. The car-seat is provided therebeneath with any suitable form of heat radiator 6, arranged lengthwise of the seat-frame and supported thereby through the medium of cross-bars 7 and 8, the ends of 50 which are bolted to the seat-frame, as at 9 and 9^a. The radiator is suspended from these cross-bars, to which it is attached by bolts 10. To suitably position it with reference to the deflector, hereinafter described, 55 each of the said cross-bars is provided with angular bends to form a depressed portion 11 in the middle thereof, where the radiator is secured. Interposed between the radiator 6 and cushion 1 of the car-seat is the heat-deflector 12. This comprises a plane-member 60 of metal or other suitable material sufficiently long to cover the radiator for its entire length, or nearly so, and sufficiently wide to extend from a point near the front of the seat-frame to the rear underneath edge 65 of the cushion. It is upwardly inclined, transversely, so that its rear edge 13 is elevated a suitable height above its front edge 13^a and extends to a point where it is in contact with the underneath rear edge of the cushion 70 1, or nearly so. The deflector is constructed at its rear elevated portion with a hood or trough 17, open at the bottom for its entire length. This trough, which is substantially of inverted U-shape, is closed at one end of the deflector, as at 18, and extends beyond the other end, as at 19, to a point near the end of the cushion 1 of the car-seat, and at this end the trough is open. The closed top 75 20 of the hood or trough is upwardly-inclined from its closed end to the open end. The object of this construction of the deflector with a hood or trough at the rear of the car-seat is to carry the rearwardly deflected heat currents to one end of the car-seat where they are discharged. The object 80 85 is to protect all of the underneath surface of the seat-cushion as far back as the said rear edge, from exposure to the heat currents from the radiator 6. The deflector 12 is 90 supported at each end and held in position with its rear edge elevated, as above stated, by means of a pair of angle-irons or brackets 14 and 15 secured to the top of cross-bars 7 and 8 and to the seat-frame. The 95 brackets 14 are L-shaped and the long arms thereof, 14^a, are bent upwardly a suitable distance from their ends to allow them to conform to the angle of inclination of the deflector as shown in Fig. 2. These arms 100 are provided with rivet-holes and are secured to the upper surface of the deflector near the front by the rivets 16. The short arms are provided with bolt-holes and are secured on the front ends of the cross-bars 105 and to the seat-frame by the said bolts 9. The angle-irons or brackets 15, which are vertically disposed, are secured to the under surface of the deflector near its rear edge by the rivets 16^a and on the rear ends of the cross- 110

bars and to the seat-frame by the said bolts 9^a. These brackets are bent in opposite directions and the bends are right-angular to form oppositely-disposed arms, which are 5 provided with rivet and bolt-holes.

In Fig. 3 a modification of heat-deflector for attachment to the seat-frame, is shown. The deflector here comprises a plane member 21 and trough 22 which may be secured 10 to the seat-frame 3 above the radiator 6 by the form of attachment hereinbefore described. The description of this plane-member is similar to that given of the plane-member 12, but, instead of the form of hood 15 or trough therefor described, which only conducts the heat currents to one end of the car-seat, the construction of the present form of deflector comprises a trough substantially of inverted U-shape, open at both ends and 20 extending from one end of the cushion 1, to the other end. The top 23 is closed and the bottom open, as described for the construction shown in Fig. 1, but it gradually slants upwardly from a point near the center 25 thereof and in opposite directions to each of the open ends. By this form of the invention the heat-currents, when deflected to the rear of the cushion 1, are conducted to both ends of the car-seat and there discharged.

30 From the foregoing description of the construction of this invention, in its different forms, it will be readily understood that the heat currents from the radiator are kept constantly in motion by the deflector 35 and conducted to the rear of the cushion of the car-seat and discharged at one or both ends of the car-seat, and not permitted to become pocketed beneath the cushion and thereby over-heat the same and make the seat 40 uncomfortable from this cause.

Having thus fully described my invention what I claim is new and desire to secure by Letters Patent of the United States, is:

1. The combination with a seat and a heat-radiator thereunder, of a heat-deflector interposed therebetween, and provided at its rear with an inverted trough shaped portion the top of which is inclined upwardly toward the end of the car seat.
2. The combination with a seat and a heat-radiator thereunder, of a heat-deflector interposed therebetween and provided at its rear with an inverted trough shaped portion the top of which is inclined upwardly toward the end of the car seat, means for removably attaching the radiator to the seat and means for removably securing the deflector to the said attaching means.
3. The combination with a seat and a

heat-radiator thereunder, of a heat-deflector 60 interposed therebetween and comprising an inclined plane-member provided at its upper part with an inverted trough shaped portion the top of which is inclined upwardly toward the end of the car seat, means for removably attaching the radiator to the seat and means for removably securing the deflector to the said attaching means.

4. The combination with a seat and a heat-radiator thereunder, of a heat-deflector 70 interposed therebetween and comprising an inclined plane-member provided at its rear with an inverted trough shaped portion the top of which is inclined upwardly toward the end of the car seat, the said portion extending laterally beyond the deflector, and being closed at the bottom of its incline.

5. A heat-deflector for radiators comprising an inclined plane-member provided at its rear with an inverted trough shaped portion the top of which is inclined upwardly toward the end of the car seat, the said portion extending laterally beyond the deflector, and being closed at the bottom of its incline.

6. A heat-deflector for radiators comprising an inclined plane-member provided at its upper part with an inverted trough shaped portion the top of which is inclined upwardly toward the end of the plane-member.

7. A heat-deflector for radiators comprising an inclined plane-member provided along its upper part with an inverted trough shaped portion the top of which is inclined upwardly toward the end of the plane-member, the said portion extending laterally beyond the deflector.

8. The combination with a car seat and a heat-radiator removably secured to the frame of the seat, of a heat-deflector between the seat and the radiator, said deflector comprising an inverted trough shaped portion the top of which is inclined upwardly toward the end of the car seat, said portion extending laterally beyond the deflector and being closed at the bottom of its incline, and supports attached to the radiator for holding it in place in the seat frame, with supporting means between the deflector and said radiator supports.

In testimony whereof I hereunto affix my signature in presence of two witnesses.

FREDERIC W. BUTT.
